L. L. HALL,
FOOD BIN,
FILED OCT. 28, 1921.

Lyman L. Hall
INVENTOR.

ATTORNEY.

UNITED STATES PATENT OFFICE.

LYMAN L. HALL, OF LOUISVILLE, KENTUCKY.

FOOD BIN.

Application filed October 28, 1921. Serial No. 511,213.

To all whom it may concern:

Be it known that LYMAN L. HALL, a citizen of the United States, residing at Louisville, in the county of Jefferson and State of Kentucky, has invented certain new and useful Improvements in Food Bins, of which the following is a specification.

This invention relates to food bins or containers and has special reference to a tilting bin or container.

One important object of the invention is to improve the general construction of devices of this character.

A second important object of the invention is to provide an improved bin or container and truck therefor, the two being arranged so that the container may be moved to tilting position or moved to a position in which it cannot be tilted.

With the above and other objects in view, the invention consists in general of certain novel details of construction and combinations of parts hereinafter fully described, illustrated in the accompanying drawings, and specifically claimed.

In the accompanying drawings, like characters of reference indicate like parts in the several views, and:

Figure 1 is a plan view of the device partly broken away.

Figure 2 is a vertical median section through the invention, the view also showing the container in tilted position in dotted lines.

In the embodiment of the invention here-illustrated there is provided a truck platform 10 having swivelling casters 11 at its corners, the platform being substantially square. At each side of this platform there is provided a vertical post or standard 12 which is braced from lateral swinging movement by diagonal braces 13. The upper end of each of these posts or standards is provided with a spaced pair of notches 14 which

extend diagonally downward from one side of the respective post to the center, the outer ends of the notches being connected by a channel 15. This channel 15 is preferably closed in by a cover plate 16 as shown in Figure 2. The bin or container proper consists of a cylindrical body 17 having handles 18 at each side. This body 17 is provided with trunnions 19 located substantially center of the height of the body. At each end 20 of the body there is provided a cover

which is hinged at one side as at 21 and is provided at its other side with suitable locking means as indicated by the hasp lock 22. The proportions of the parts are such that the bottom of the container 17 lies close to the platform 10 with the trunnions 19 in the normal position as shown in Figure 2. When in this position it will be obvious that the bin cannot be tilted to any extent. When it is desired to tilt the bin the handles 18 are grasped and the trunnions 19 moved up through the channel 15 and dropped into the upper notch 14 thus assuming the position 19'. When in this position the bottom of the container is sufficiently elevated to permit swinging movement as indicated by the dotted lines in Figure 2 so that the container can be dumped and it will be obvious that, by reason of the double ended construction, the dumping may be effected from either end.

There has thus been provided a simple and efficient device of the kind described and for the purpose specified.

It is obvious that minor changes may be made in the form and construction of the invention without departing from the material principles thereof. It is not therefore desired to confine the invention to the exact form herein shown and described, but it is wished to include all such as properly come within the scope claimed.

Having thus described the invention, what is claimed as new, is:

1. The combination with a wheel supported platform; of standards at each side of the platform provided adjacent their upper ends each with a pair of inwardly and downwardly extending notches and a channel connecting the outer ends of these notches, a cover plate covering the channel, a bin located between said standard, and trunnions on the bin normally resting on the lower notches, said trunnions being adapted to be moved upward through said channel into the upper notch to permit tilting of the bin.

2. The combination with a wheel supported platform; of standards at each side of the platform provided adjacent their upper ends each with a pair of inwardly and downwardly extending notches and a channel connecting the outer ends of these notches, a cover plate covering the channel, a bin located between said standards, and

trunnions on the bin normally resting in the lower notches, said trunnions being adapted to be moved upward through said channel into the upper notches to permit 5 tilting of the bin, said trunnions being located centrally of the height of said bin whereby the bin may be completely inverted, and the bin being provided with a hinged closure at each end whereby each 10 end of the bin may be used for either filling or discharge.

3. The combination with a wheel supported platform; of standards at each side of the platform provided adjacent their upper ends each with a pair of inwardly and 15

downwardly extending notches, a bin located between said standards, and trunnions on the bin normally resting in the lower notches, said trunnions being adapted to be moved upward into the upper notches to 20 permit tilting of the bin, said trunnions being located centrally of the height of said bin whereby the bin may be completely inverted, and the bin being provided with a hinged closure at each end whereby each end 25 of the bin may be used for either filling or discharge.

In testimony whereof I affix my signature.

LYMAN L. HALL.
